UNITED STATES PATENT OFFICE.

GEORGE L. ROLLINS, OF BRIDGEWATER, MASSACHUSETTS, ASSIGNOR TO W. H. McELWAIN COMPANY, OF BOSTON, MASSACHUSETTS, A CORPORATION OF MASSACHUSETTS.

MACHINE FOR APPLYING REINFORCEMENT TO INSOLES.

1,210,696.

Specification of Letters Patent.

Patented Jan. 2, 1917.

Application filed December 28, 1911. Serial No. 668,257.

To all whom it may concern:

Be it known that I, GEORGE L. ROLLINS, of Bridgewater, in the county of Plymouth and State of Massachusetts, have invented 5 certain new and useful Improvements in Machines for Applying Reinforcement to Insoles, of which the following is a specification.

The object of the present invention is to 10 provide a machine capable of applying a reinforcing strip in the angle between an upstanding rib or channel lip on an insole and the surface of the sole within said lip. The particular insole upon which this machine is designed to act is channeled from a 15 line well within the edges of the sole outwardly toward such edges, and the flap formed by channeling is turned up. This leaves a depression in the face of the sole on 20 the inner side of the lip, which depression is equal in width to the height of the lip, and in depth to the thickness of the lip. The purpose of the machine in which my 25 present invention is embodied is to place a reinforcing strip in this depression and against the inner face of the lip.

To this end the machine comprises, essentially, guiding means for the reinforcing strip, a device for crowding the strip into 30 the angle, between the lip and the face of the sole, and means for supporting and feeding the sole while the strip is in process of being applied.

A possible embodiment of the invention, 35 which at the present time I consider preferable to others is illustrated in the accompanying drawings, in which,

Figure 1 represents a side elevation of the machine. Fig. 2 is a plan view. Fig. 3 is 40 a rear elevation. Fig. 4 is a side elevation of the operative elements of the machine as seen from the side opposite to that represented in Fig. 1. Fig. 5 is a plan view of the same elements. Fig. 6 is a sectional view of the same elements on line 6—6 of Fig. 4. Fig. 7 is a cross-section of the strip 45 guide taken on line 7—7 of Fig. 6.

The same reference characters indicate 50 the same parts in all the figures.

Referring to the drawings, 1 represents the frame of the machine which is adapted to be set upon a bench or table. This frame is provided with bearings 2, 3 in which is

rotatably held a shaft 4, and with an inclined bearing 5 containing the shaft of 55 an inclined work-supporting and feeding member 6, which is here shown as a table having a plane supporting face perpendicular to its axis. The shaft 4 carries a bevel gear 7 which meshes with a complementary 60 bevel gear 8 on the shaft of the table and imparts rotation to the latter.

The drive to the shaft 4 is through a belt pulley or other driving element 9, a shaft 10, carrying a worm 11, and a worm wheel 12 65 secured to the shaft 4 and meshing with the worm 11. The pulley 9 is loose on the shaft and may be connected therewith when the machine is to be set in motion, by a clutching device under the control of the operator. 70 Such clutching device is not part of the present invention and may be any of the known forms of clutch. The one which I have chosen for my purpose is a simple form of friction clutch consisting of a disk 13 secured upon the shaft 10 and having a facing 14 of frictional material such as leather. The pulley 9 is adapted to be pressed against this facing and is therefore slidably mounted on the shaft, and is controlled by a bell 80 crank 15 pivoted upon a bracket 16, and a treadle 17 connected with the bell crank by a link 18. One of the arms of the bell crank has studs 19 projecting into a groove 20 in the hub of the pulley. Springs 21 and 22 85 acting on the bell crank and treadle respectively tend to disconnect the clutch, making the machine normally inoperative. The link 18 passes through the table on which the machine is set and the treadle is pivoted to 90 a bracket 23 secured to the floor, in easy reach of the operator's foot.

The tool or element which performs the work of tucking the reinforcing strip into the angle between the channel lip and the 95 face of the sole is conveniently a disk or wheel 24 which is so arranged relatively to the table 6 that its periphery can enter the angle referred to, which, for convenience of description I prefer to call the inner "lip 100 angle", of an insole properly placed upon the table. This disk is driven positively in unison with the table and in relatively the same direction by a gear wheel 25 secured upon the shaft 4 which meshes with a pinion 105 26 secured upon the shaft 27 which carries

the disk 24. For convenience of description I may term such disk or wheel the setting wheel.

The shaft 27 is held in a bearing 28 on an arm 29 which is adapted to swing about a pivot stud 30 secured in a bracket 31 which rises from the frame 1. In order to stiffen the bearing which the arm 29 has on the pivot, such arm is preferably formed 10 with a sleeve 32, extending out to one side and giving an increased length to the bearing surface. The pivot 30 is placed directly above the gears 25 and 26, approximately in the same plane therewith and in the line 15 of centers thereof, so that a considerable range of swinging movement is permitted to the arm 29 without bringing the gears out of mesh. An adjustable stop 33 in the form of a set screw passing through a lug 20 34 on the bracket 31 provides a variable limit for the movement of the swinging arm in one direction. A spring 35 connected at one end to an eye 36 on the machine frame, and at the other end to the 25 swinging arm 29, normally holds such arm yieldingly against the stop 33 and thereby retains the swinging arm and the setting wheel 24 in the position shown in Fig. 1. This spring is indicated as broken away in 30 Fig. 1, in order not to obscure the parts behind it. The connection of the spring with the swinging arm 29 provides for an adjustment of the tension of the spring and is effected conveniently in the following 35 manner. An eye bolt 37 is connected to the spring and passes through a lug 38 projecting from a portion of the arm 29. A thumb nut 39 on the eye bolt enables the same to be drawn through the lug 38 to a greater 40 or less extent, and thereby to stretch or slacken the spring.

It is necessary to lift the setting wheel whenever work is placed in or taken from the machine. This lifting is accomplished 45 by a treadle 40 (see Fig. 3), which is connected through a link 41 with a lever 42 pivoted upon a stud 43 and having an arm lying under a foot 44 on the arm 29. As will be readily understood depression of the 50 treadle 40 causes the setting wheel to be first swung to the right and then upwardly (with reference to Fig. 1) far enough to widen the space between the setting wheel and the table.

55 Adjacent to the table is a support or guide 45 for the edge of the sole, such guide being a roll mounted so as to turn freely upon an upright pivot. It is so grooved as to provide a conical face, which is located 60 close to the edge of the table 6 at one point, and at this point is approximately perpendicular to the plane of the table. The movement of the setting disk away from the table also takes it away from the guide.

65 The final element to be described is a

guide for the reinforcing strip. Such strip 70 guide consists of a block 46 mounted adjustably on a projection 47 extending from the arm 29. Such block has a tail 48 extending close to the setting wheel and notched at its end to admit the rim of the wheel. The guideway for the strip is 75 formed between two flanges 49, which flanges have lips 50 projecting toward one another in that portion of their length nearest to the wheel. The reinforcing strip, 80 represented at 51, which is preferably a strip of heavy cloth such as canvas, coated on one side with an adhesive, is fed through the guideway to and under the setting 85 wheel.

Figs. 4, 5 and 6 show an insole 52 in operative position, with an upturned channel 90 lip 53 and a channel 54 inside of the lip. The reinforcing strip is intended to fill this 95 channel and to lie against the inner face of the lip, extending preferably to the outer edge of the latter. The sole is placed flat on the table 6 with its smooth or unchanneled face, that is, the surface opposite to 100 the one from which the lip projects against the table, and its edge against the guide roll 45, the setting wheel having been lifted in the manner described. The sole is so placed that the beginning point of the channel lies directly in front of the setting wheel, and the heel portion of the sole projects in the direction of feed. The setting wheel with the reinforcing strip placed 105 under it is then allowed to return to normal position, in which it is held by the spring 35 with its rim pressing into the angle formed by the channel lip. Preferably such rim is brought to a fine edge, in order that it may enter well into the angle. 110 Thereupon the machine is set in motion and the simultaneous rotation of the table 6 and setting wheel causes the sole and the reinforcing strip to be fed in unison, the strip being drawn through the guide and 115 laid in the channel. It should be noted that in order to obtain this result the setting wheel is arranged with the plane of its rim approximately vertical and the table is on a slant of approximately 45° upwardly and 120 outwardly from the setting wheel, whereby the plane of the setting wheel makes an acute angle with the face, or supporting element, of the table.

Another point of importance to be noted 125 is that the setting wheel does not bear on the face of the sole or press against the lip, but bears only in the angle between the lip and the face of the sole. This will be recognized from an inspection of Fig. 4, which 130 shows the point clearly. Although the sole edge guide 45 has a flange adjacent to the lip, yet this flange is at such a distance from the setting wheel that the lip is unconfined and is subjected to no pressure whatever, 135

except such slight pressure as its own stiffness causes it to exert against the setting wheel, which is inappreciable. In fact the face of the setting wheel might be even more sharply beveled than as here shown without changing in any way its effect on the work. The point is that the wheel is designed to bear only on the center line of the strip and press this center line in the lip angle. I have found that better results are secured in this way, as the reinforce is tucked more completely and more firmly into the lip angle and its sides adhere sufficiently to the lip and to the face of the sole. It is to be noted that the guide 45 is not in any sense a support for the channel lip, but solely a guide for guiding the edge of the sole.

Another important feature is that the setting wheel is so placed that an imaginary line drawn to it from the pivot 30 is approximately perpendicular to the face of the table 6. In consequence the commencement of movement of the wheel away from the guide 45 is perpendicular to such imaginary line, and therefore approximately parallel to the table, hence a certain amount of such movement is permitted before the distance between the wheel and table increases to any appreciable degree. This arrangement is provided in order to accommodate variations in the amount by which the edge of the sole projects beyond the lip. It is to be remembered that the distance between the lip and the edge of the sole is least at the part which lies outside of the ball of the foot, is greater at the toe, and greatest at the shank. As the sole is fed past the guide 45 those portions of the base of the lip which lie more or less remote from the edge of the sole cause the setting wheel to move slightly toward and from the guide, but in this movement the distance of the setting wheel from the table is not appreciably increased and so the wheel is not withdrawn from the lip angle, and no additional pressure is brought to bear against the lip.

I claim,—

1. A machine for applying a reinforcing strip to the angle within the lip of an insole, including a supporting and feeding table for the insole, an unyielding guide for the edge of the insole, and a setting wheel having a rim arranged in a plane making an acute angle with the plane of the table and located at such a distance from the guide as to enter the angle on the inner side of the lip, said wheel being also arranged to yield away from the sole edge.

2. A machine for applying a reinforcing strip to the angle within the lip of an insole, including a supporting and feeding table for the insole, a guide for the edge of the insole, a setting wheel having a rim arranged in a plane making an acute angle with the plane of the table and located at

such a distance from the edge guide as to enter the angle on the inner side of the lip, and a strip guide having a discharge point adjacent to the rim of said wheel.

3. A machine for applying a reinforcing strip in the angle between the surface of an insole and a rib standing up from such surface, comprising a supporting and feeding member adapted to engage the surface of the insole opposite to that from which the rib projects, an insole guide arranged to control the direction of feeding of the insole, and a setting wheel having faces oblique to its axis meeting in a circular edge the plane of which is perpendicular to such axis, arranged with the plane of such rim at an acute angle to the insole-engaging element of said member.

4. A machine for applying a reinforcing strip in the angle between the surface of an insole and a rib standing up from such surface, comprising a supporting and feeding member adapted to engage the surface of the insole opposite to that from which the rib projects, an insole guide arranged in such relation to said member as to contact with the edge of an insole which is operatively engaged with the member, and constructed to leave the rib free, and a setting wheel having a rim shaped to enter the lip angle of an insole and located in a plane which makes acute angles with the work engaging elements of both the said member and the said guide.

5. In a machine of the character described, the combination with a support for an insole, of a setting wheel having beveled faces meeting at an edge which is adapted to enter the angle between the lip and face of an insole, the face of the setting wheel which is in use is nearest the surface of the insole being arranged at such an angle to the insole engaging element of said support as to recede from the surface of the insole, whereby the wheel engages the insole only at its rim.

6. A machine of the character described, comprising a work-supporting and feeding table having a plane supporting face, a guide for the edge of a sole, arranged to make contact with the edge of a sole supported by said table, and a setting wheel arranged relatively to said table and gage so as to enter the angle between the sole and the lip on the inner side of the lip, said wheel being yieldingly mounted and movable away from the gage in a direction substantially parallel to the face of the table.

7. A machine of the character described, comprising a work-supporting and feeding table, a gage for the edge of a sole, and a setting wheel arranged relatively to said table and gage so as to enter the angle between the sole and the lip on the inner side of the lip, and a pivotally movable holder

for said wheel so arranged that a line extending from the wheel to the pivot of said holder is substantially perpendicular to the face of the table, whereby the wheel may move away from the gage without substantially altering its distance from the table.

8. A machine of the character described comprising a guide for a fabric strip, a setting wheel having beveled faces meeting in a peripheral rim arranged near the delivery point of said guide and in such position as to engage the strip between its edges, and supporting means for an insole arranged with its supporting portion making oblique angles with both the plane of said rim and with the axis of the wheel, whereby to support such sole with the lip on one side of the wheel rim and a face of the sole on the other side of such rim and out of contact with the adjacent beveled face of the wheel.

9. A machine for applying a reinforcing strip in the lip angle of an insole, comprising a support for the insole, a guide extending transversely to the supporting element of said support in position to engage the edge of an insole placed on said support, a setting wheel having its operative portion tapered to an edge and located so that the plane of such edge makes an acute angle with the operative elements of the said support and guide, the said guide constructed to leave the lip of the insole unsupported and the wheel being beveled so as not to bear on the surface of the insole adjacent to the lip, and means for feeding a reinforcing strip arranged to deliver the strip between the setting wheel and the said support, with the median line of the strip approximately in the plane of the edge of the wheel.

10. A machine for applying a reinforcing strip to insoles, comprising a rotary supporting and feeding table, a rotary setting disk having its axis oblique to that face of the table which engages the insole, and having conical faces meeting at a relatively fine edge, which is adapted to enter the angle between the face and the lip of an insole placed upon the table and on the inner side of the lip, means for feeding a strip continuously to said disk, arranged to present a part of the strip intermediate its edges to the edge of the disk, and means for rotating the table and disk together, whereby to feed the sole and continuously apply the strip at one and the same time.

11. A machine of the character described

comprising a rotary table constructed and arranged to engage the face of an insole opposite to the face from which the rib projects, means for rotating the same, an edge guide adjacent to the edge of said table arranged with its operating face crossing the plane of the table in position to engage the edge of an insole supported by the table, a rotating reinforce setting wheel in geared relation with said table so as to rotate in unison therewith, and a movable holder supporting said wheel and so arranged that the latter may be displaced toward and away from said edge guide.

12. A reinforce setting machine comprising a complemental table and setting wheel, the latter being arranged to rotate in a plane which makes an acute angle with the face of the table, means including complemental gears connecting said table and wheel to cause them to rotate in unison, and a pivotally mounted holder for the wheel and one of such intermeshing gears, the pivot of which is in the plane of the gears and in a line passing from the wheel approximately perpendicular to the table, whereby movement of the holder is permitted without affecting the mesh of the gears, and without withdrawing the wheel from the table.

13. A machine for setting a reinforce in the inner lip angle of an insole, comprising a supporting and feeding member for the insole, a guide arranged to engage the edge of an insole supported on said member, and a setting wheel arranged at a distance from said edge guide substantially equal to the distance of the inner lip angle of an insole from the edge thereof.

14. A machine for setting a reinforce in the inner lip angle of an insole, comprising a supporting and feeding member for the insole, a guide arranged to engage the edge of an insole supported on said member, a setting wheel arranged at a distance from said edge guide substantially equal to the distance of the inner lip angle of an insole from the edge thereof, and a strip guide arranged to deliver a reinforcing strip with its median line approximately in the plane of the rim of said wheel.

In testimony whereof I have affixed my signature, in presence of two witnesses.

GEORGE L. ROLLINS.
